(57) **CLAIM**

We claim the ornamental design for a cooktop with back splash, as shown and described.

DESCRIPTION

FIG. 1 is a top perspective view of a cooktop with back splash showing our new design.

FIG. 2 is a front view of the cooktop with back splash shown in FIG. 1.

FIG. 3 is a right elevation view of the cooktop with back splash shown in FIG. 1.

FIG. 4 is a left elevation view of the cooktop with back splash shown in FIG. 1; and,

FIG. 5 is a top plan view of the cooktop with back splash shown in FIG. 1.

The broken line showing of environment in the drawings is for illustrative purposes only and forms no part of the claimed design.
